US0D1104008S

(12) **United States Design Patent** (10) **Patent No.:** **US D1,104,008 S**
(45) **Date of Patent:** **** Dec. 2, 2025**

(54) **DISPLAY PANEL WITH GRAPHICAL USER INTERFACE**

(71) Applicant: **Samsung Display Co., Ltd.**, Yongin-si (KR)

(72) Inventors: **Hyeon Jun Lee**, Yongin-si (KR); **Chul Kim**, Yongin-si (KR); **Gyeong-Ub Moon**, Yongin-si (KR); **Jongyeop An**, Yongin-si (KR); **Dong Wook Yang**, Yongin-si (KR)

(73) Assignee: **Samsung Display Co., Ltd.**, Yongin-si (KR)

(**) Term: **15 Years**

(21) Appl. No.: **29/871,845**

(22) Filed: **Feb. 28, 2023**

(30) **Foreign Application Priority Data**

Jan. 4, 2023 (KR) 30-2023-0000430
Jan. 4, 2023 (KR) 30-2023-0000431
Jan. 4, 2023 (KR) 30-2023-0000432

(51) **LOC (15) Cl.** **14-04**

(52) **U.S. Cl.**

USPC **D14/485**

(58) **Field of Classification Search**

USPC D14/485-495

(57) **CLAIM**

The ornamental design for display panel with graphical user interface, as shown and described.

DESCRIPTION

FIG. 1 is a front view of a first embodiment of the display panel with graphical user interface according to our new design; and,

FIG. 2 is a front view of a second embodiment of the display panel with graphical user interface according to our new design.

The broken lines indicate unclaimed portions of the article that form no part of the claimed design.

1 Claim, 2 Drawing Sheets
